United States Patent Office

Des. 176,810
Patented Jan. 31, 1956

176,810

EAR RADIO

John R. Norris, Phoenix, Ariz.

Application May 19, 1955, Serial No. 36,127

Term of patent 14 years

(Cl. D56—4)

Fig. 2

Fig. 1

Fig. 3

Fig. 1 is a front elevation of the ear radio embodying my new design.

Fig. 2 is a plan view of the ear radio shown in Fig. 1.

Fig. 3 is a perspective view of the ear radio shown in Figs. 1 and 2.

I claim:

The ornamental design for an ear radio, as shown.
